HENRY H. HAYDEN, OF NEW YORK, N. Y., ASSIGNOR TO HOLMES, BOOTH, AND HAYDENS, OF WATERBURY, CONNECTICUT.

Design No. 3,292, dated December 15, 1868.

DESIGN FOR A FORK OR SPOON-HANDLE.

The Schedule referred to in these Letters Patent and making part of the same.

To all whom it may concern:

Be it known that I, HENRY H. HAYDEN, of the city and State of New York, have invented and made a certain new and original Design for Ornamenting the Surface of the Handles of Forks or Spoons; and I do hereby declare the following to be a correct description of the said design, reference being had to the annexed photographic views, representing, in

Figure 1, the design upon the handle of a spoon, and in

Figure 2, the design upon the handle of a fork.

The design of the ornamentation for the handles of forks, spoons, or similar articles of table-furniture, consists in the peculiar shape and configuration of the ornamental bead-work that runs around near the edge of the handle.

This ornamental bead-work consists of a groove at 1, near the edge of the handle, then a rounded bead at 2, merging into a shallow broad concave groove, 3,

rising to a low rib at 4, that terminates at right angles, or nearly so, to the surface of the handle at 5.

This character of broad shallow ornamental bead-work or moulding follows the contour of the outline of the handle, and has a very neat and massive ornamental appearance.

The section, fig. 3, represents the shape of this ornamental bead or moulding.

What I claim, and desire to secure by Letters Patent, is—

The design of the ornamental bead-work or moulding described and represented.

In witness whereof, I have hereunto set my signature, this day of November, A. D. 1868.

H. H. HAYDEN.

Witnesses:

CHAS. H. SMITH,
GEO. D. WALKER.
